UNITED STATES PATENT OFFICE.

HENRY G. WOLCOTT, OF MATTEAWAN, NEW YORK.

POUNCING OR FINISHING OF FELT OR OTHER LIKE ARTICLES.

SPECIFICATION forming part of Letters Patent No. 394,747, dated December 18, 1888.

Application filed June 7, 1887. Serial No. 240,519. (No model.)

To all whom it may concern:

Be it known that I, HENRY G. WOLCOTT, of Matteawan, in the county of Dutchess and State of New York, have invented a new and 5 useful Improvement in the Pouncing or Finishing of Felt or other like Articles, of which the following is a full, clear, and exact description.

This invention has for its object the pouncing, or "finishing," as it is sometimes termed, of irregular-shaped goods—such, for instance, as boots and shoes—made from or of felt, or articles into which wool, hair, or fur enter or form a part. Heretofore in the pouncing or 15 finishing of such irregular-shaped articles—that is, the removing of the fuzzy ends or portions of the material which unavoidably form or stand out on the surface of such goods—it has been customary to do such 20 work by hand—as, for instance, by sand or emery paper held in the hand and rubbed over the surface of the goods while on their last or former. This is both a tedious and expensive operation, and the goods being of 25 an irregular shape it has not been practicable, without cutting into or through certain parts of the articles, to substitute the ordinary sand or emery wheel for such work.

My invention consists in a rapidly-revolving flap-like beater for pouncing or finishing such irregular-shaped articles by subjecting them while on their lasts to the action of said beater, the acting flaps or surfaces of which are of a granulated cutting and abrading 35 character—such as sand or emery paper—and that operate in a free or loose manner upon the lasted article as the latter is turned about or manipulated to present successively the several portions of its surface to rubbing 40 contact with the abrading-flaps.

The invention also consists in certain novel constructions and combinations of parts in the revolving pouncer or finisher, for the purpose above described, substantially as hereinafter described, and pointed out in the 45 claims.

Reference is to be had to the accompanying drawings, forming a part of this specification, in which similar letters of reference indicate 50 corresponding parts in all the figures.

Figure 1 represents a side view of a circular or revolving flap-like pouncer with a felt

boot or shoe exposed to the action thereof in illustration of the operation of my invention. Fig. 2 is a side view of a special construction 55 of the revolving flap-like pouncer; Fig. 3, a transverse section of the same upon the line *x* *x* in Fig. 1, and Fig. 4 a partial longitudinal section thereof mounted and ready for use. Fig. 5 is a transverse section upon the line *y* *y* 60 in Fig. 6 of the revolving flap-like pouncer under a modified construction, and Fig. 6 a side view of the same with one of its sides removed.

In Fig. 1, A indicates a revolving pouncer 65 or finisher, preferably of cylindrical contour, armed on its peripheral surface with a series of flap-like beaters, B, held by or secured at their one end to the body of the pouncer, and each of which is composed of a strip of sand-paper, *b*, and a rubber or other flexible backing-piece, *c*. Emery-paper or sand or emery cloth may be substituted for the sand-paper, if desired, and are the equivalents thereof. This pouncer is revolved with its cutting and 70 abrading material—that is, the sand-paper *b* of the beaters—in advance, as shown by arrow in Fig. 1, so that when a felt boot or shoe, C, for instance, on its last D is held and manipulated or turned about, so as to expose different parts of its surface to the action of the beaters B, the sand-paper *b* or its equivalent, supported by the rubber or flexible backing *c*, will act in a free or loose manner, but with a certain firmness due to the backing *c* upon 75 the boot or shoe to remove the fuzzy ends or portions of the material which stand out on its surface. In this way the boot or shoe may be pounced or finished in a very cheap, rapid, and perfect manner without any danger of 80 cutting into it at protruding or irregular portions of it.

The sand-paper strips *b* or their equivalent may project at their outer ends more or less beyond the rubber or flexible supporting strips *c*, as shown. As, however, it is only the sand-paper or its equivalent which is exposed to wear by contact with the article to be pounced, it is desirable that provision should be made for readily renewing such portions 95 of the pouncing-flaps as occasion may require, without renewing the flexible strips which support the abrading ones and which are not exposed to wear. This I mainly provide for 100

by extending the sand-paper or its equivalent within the body of the pouncer, and so that the same can readily be drawn out from time to time through openings in the peripheral portion of the body, to keep up a proper outside supply of the abrading material as it becomes worn or useless, and to renew the abrading material when required. Figs. 2, 3, and 4 illustrate one construction of revolving 5 pouncer which provides for doing this. In these figures the body of the pouncer A is constructed of two clutch-like sections, A' A², with tapering inner facial projections, d, adapted to engage said sections in a free or 10 loose manner with each other, so as to leave openings e between the projections d for the flaps or beaters B of sand-paper b or its equivalent, and flexible supporting-strips c, both of which project beyond the exterior of 15 the body, and also enter within it. The one of these sections, A', rests against a collar, f, upon a mandrel, E, which carries and rotates the pouncer, and which is provided with fast and loose pulleys F G to rotate the pouncer 20 or to arrest its motion, as required. The other section, A², is adjusted upon the mandrel E toward or from the adjacent section A' by tightening or slackening a nut, h, fitted to screw upon the end of the mandrel back of 25 the section A². This adjustment of the section A² provides for clamping or holding the flaps B in position between the projections d of the two sections A' A², and for releasing them when it is required to replace the sand- 30 paper b or to draw it partially out to replace an outer worn end portion, which may be cut off.

Figs. 5 and 6 of the drawings show the body of the rotary pouncer A as composed 35 in part of a main hollow cylindrical body portion, A³, having a hub, k, for supporting the pouncer upon its driving-mandrel E against the collar f, upon which it bears or rests upon its one side or face. The opposite 40 side or face is formed of a loose face-plate or cover, A⁴, capable of sliding longitudinally upon the mandrel E, subject to adjustment in this direction by a nut, h, fitted to screw upon the outer end of the mandrel, as in the 45 case of the pouncer shown in Figs. 2, 3, and 4. Fitted around the hub k of the section A³ is a sleeve, H, of leather or other suitable flexible material, and of a length somewhat greater than the hub k, so that it will project beyond the outer end thereof and bear 50 against the face-plate A⁴. The series of strips b, of sand-paper or its equivalent, are tacked or otherwise secured at their one end to the sleeve H and wound around the same, 55 while the outer end portions of said strips are passed out through slots l in the peripheral portion of the body-section A³ for operation, as hereinbefore described, in connection with the rubber or flexible supporting- 60 strips c, secured to the peripheral portion of 65

the section A³, and bearing on or against the backs of the abrading-strips b of the flexible beaters B. This construction of the pouncer provides for an increased amount of sand-paper or abrading material being stored 70 in the body of the pouncer to keep up the supply as wear renders necessary. The paper is held in place, when sufficiently drawn out through the slots l, by tightening up the nut h and forcing up the cover A⁴, so as to bind 75 or bear upon the outer end of the flexible sleeve H. As the strips b, however, become worn on their outer acting end portions, the nut h is slackened, so as to relieve the sleeve H from being bound by the cover A⁴ and to 80 admit of the sleeve H turning upon the hub k, when or after which the strips b may be pulled or drawn out, as shown in Fig. 5, for one of said strips to expose fresh abrading-surfaces and the old or worn end portions be cut 85 or torn off and the cover A⁴ be tightened up again.

Having thus described my invention, what I claim as new, and desire to secure by Letters Patent, is—

1. A pouncing or finishing device for felted and other like articles, composed of a rotatable body portion and a series of exterior flaps of sand-paper or its equivalent attached to and arranged around the body portion at suitable 95 distances apart, essentially as specified.

2. In a pouncing or finishing device for felted and other like articles, the combination of a mandrel and a cylinder or body mounted thereon, provided on its exterior or periphery 100 with a series of flaps of sand-paper or its equivalent, substantially as described.

3. In a pouncing or finishing device for felted and other like articles, the combination of a rotatable body portion and a series of 105 attached flexible flaps or beaters arranged to project from and around the same, and composed of strips of sand-paper or its equivalent and independent flexible supporting-strips on the backs thereof, essentially as 110 specified.

4. In a pouncing or finishing device for felted and other like articles, the combination of a rotatable mandrel, a cylinder or body mounted thereon, composed of independent 115 sections adjustable the one toward the other upon the mandrel, and adapted to hold abrading-strips of sand-paper or its equivalent within them, and the strips of sand-paper or its equivalent contained within the body and arranged to project as flexible flaps beyond and around the exterior thereof, and adapted to be drawn out or extended therefrom as required, substantially as and for the purpose or purposes herein set forth.

HENRY G. WOLCOTT.
